FIG. 1

FIG. 1 is a front view of the building and is typical of the other three sides of the building in showing the several story projections around the cylindrical shaped center portion of the building in their spiral rise from bottom to the top around the building.

FIG. 2 is a top plan view of the building.

FIG. 3 is an enlarged side view of several stories of the building showing the typical design of the several floors and having parts broken away for further illustrating the design of the building.

FIG. 4 is a horizontal sectional view through the building the view being as seen from the line IV-IV in FIG. 3 and looking in the direction of the arrows.

I claim:

The ornamental design for a building, as shown and described.
